UNITED STATES PATENT OFFICE

95,040

DESIGN FOR A STEERING WHEEL FOR AUTOMOBILES

Emil L. Herbolsheimer, Defiance, Ohio, assignor
to The Defiance Pressed Steel Company,
Defiance, Ohio, a corporation of Ohio

Application July 26, 1934, Serial No. 52,709

Term of patent 7 years

To all whom it may concern:

Be it known that I, Emil L. Herbolsheimer, a citizen of the United States, and resident of Defiance, county of Defiance, and State of Ohio, have invented a new, original, and ornamental Design for a Steering Wheel for Automobiles, of which the following is a specification, reference being had to the accompanying drawing, forming a part thereof.

Figure 1 is a top plan view of a steering wheel showing my new design, and Fig. 2 is an edge

view of the steering wheel, the configuration of the hub being conventional.

The dominant feature of my design resides in the configuration of the spoke.

I claim:

The ornamental design for a steering wheel for automobiles, substantially as shown and described.

In testimony whereof I have hereunto signed my name to this specification.

EMIL L. HERBOLSHEIMER.
